SWAGING MACHINE

Harry A. Douglas, Bronson, Mich.

Application December 15, 1932, Serial 647,327
Renewed August 20, 1934

15 Claims. (Cl. 81—15)

This invention relates to swaging machines, and among the objects of the invention are the provision of a swaging machine in the form of a hand swage operable by one hand of a user, and the provision in a swaging machine of new and improved automatic means for limiting the pressure exerted upon the article.

The invention is of particular utility in its embodiment, as here illustrated, in a tool for swaging metallic terminal members to metallic electrical conductor means. A particular object of the invention is to provide an efficient and convenient hand tool of this character for expeditiously and economically making couplings such as disclosed in my copending application for patent Serial No. 727,503, filed May 25, 1934.

The full objects and advantages of my invention will appear in connection with the detail description of the herein disclosed embodiment thereof and the novel features of my inventive concept will be particularly pointed out in the claims.

In the accompanying drawings which form a part of this specification—

5 Figure 1 is a plan view of a tool embodying my invention;

Figure 2 is a partial view similar to Figure 1, but showing a different operative position, parts being removed or shown in section to illustrate the internal construction;

Figure 3 is a section taken on the line 3—3 of Figure 2;

Figure 4 is a view of the operating head on a somewhat larger scale with parts removed to show the internal construction, taken on the line 4—4 of Figure 5;

Figure 5 is a section taken on the line 5—5 of Figure 4; and

Figure 6 is a fragmentary section taken on the line 6—6 of Figure 4.

Referring in detail to the construction shown in the drawings, the illustrative tool includes an operating head 1 and operating handles 2 and 3. The head 1 may comprise a cylindrical housing 4 in which is centrally fixed a cylindrical carrier block 5, screws 6 passing through the housing and threadedly received in the block securing the housing and block together. The heads of the screws 6 are desirably countersunk to be flush with the outer surface of the cylinder 4. The face 8 of the carriage block 5 has a plurality of radial grooves 7, desirably more than two and in this instance four, and with four radial grooves 7 the grooves are advantageously diametrically arranged and ninety degrees apart, converging at

a center common to the block and housing. In each of the grooves 7 is reciprocally received a jaw 9, each of which desirably has a somewhat U-shape point 10 at its inner end and directed toward the common center. Each of the grooves 7 is laterally enlarged as best shown at 11 (Figs. 4 and 6) and each of the jaws 9 carries a lateral projection 12 which moves in the lateral enlargement of the groove pressed upon by a relatively light coil spring 13 disposed in the lateral enlargement 11 between the projection 12 and the inner end of the enlargement. The enlargements 11 are desirably of cylindrical shape to correspond with the shape of the coil springs 13 and provide a spring barrel therefor. The jaws 9 are received in the grooves 7 flush with the face 8 of the carrier block and the springs 13 normally maintain the jaws with their outer ends 14 projected radially beyond the periphery 15 of the carrier block 5. For moving the jaws 9 inwardly against the pressure of the springs 13, I provide a cylindrical annulus 16 snugly but rotatably received between the periphery 15 of the carrier block 5 and the internal surface of the housing 4. In a non-operative position of the annulus 16 the outer ends 14 of the jaws 9 are received in recesses 17 in the internal periphery of the annulus 16, said outer ends being moved into said recesses by the springs 13. When the annulus 16 is rotated by means later described, relatively to the carrier block 5, cam surfaces 18 which merge into the surfaces of the recesses 17 engage the outer ends 14 of the jaws and force the jaws inwardly and centripetally of the carrier block as shown in Figure 2. The outer ends of the jaws may be provided with rollers 19 to afford an anti-friction bearing between the jaws and the annulus.

Over the parts, as shown in Figure 4, I desirably secure a disc 20 as by screws 21 similar to the screws 6, passing through the disc and into the carrier block 5. The disc 20 is desirably flush with the jaws 9, carrier block 5, and annulus 16, and serves as a closure for one end of the housing, assisting at the same time in maintaining the parts in assembly. The disc 20 serves also as a guide plate for an article to be operated upon by the tool, such as the metallic terminal member 22, which is to be coupled with the metallic conductor 23. As shown in Figure 5, the conoidal tip 24 of the terminal member 22 is passed through a central aperture 25 in the disc 20 which aperture is concentric with the common center of the jaws 9. The walls of the aperture 25 are tapered similarly to the taper of the tip 24 to limit the extent of insertion of the tip there-

through to an extent such that the V-shape ends 10 of the jaws engage the tip 24 near its extremity and thus, when forced inwardly as described, swage this tip and the tip 26 of the 5 wire 23 to couple the terminal member and wire securely together. That is, as described in my co-pending application above referred to, the bore of the terminal member 22 which receives the wire 23 is sufficiently reduced in cross-sectional 10 area by the jaws 9, as at 26a (Figure 2), to deform the wire 23 as at 26b, reducing it in cross-section and providing interengaging shoulders between the wire and the bore of the terminal.

To relatively rotate the housing 4 and annulus 15 16, I provide these members, as here shown, with integral lugs 27 and 28, respectively, which are radially projected in a common plane, the housing being slotted as at 29 to permit the lug 28 of the annulus to project therethrough and to 20 move laterally therein as the annulus is rotated relatively to the housing. The operating handles 2 and 3 are the longer lever arms of levers 30 and 31, respectively, which are pivoted together in cross relation. The shorter lever arms 32 and 25 33 of the levers 30 and 31, respectively, are here shown bifurcated. The lever arm 32 receives between its bifurcated ends the lug 27 of the housing 4 and is articulated therewith as by the screw bolt 34. Similarly, the lever arm 33 of the lever 30 31 receives between its bifurcations the lug 28 of the annulus 16 and is articulated thereto as by the screw bolt 35. Thus when the handles 2 and 3 are squeezed together, the annulus and housing are relatively rotated and the terminal 35 member 22 and wire 23 compressed, as described. If the levers 30 and 31, however, were pivoted together upon the ordinary fixed pivot it would frequently happen that the operator would place too much or too little pressure upon the terminal 40 45 which would produce either insufficient compression to effect a secure coupling or too great compression which might break the terminal or the wire or both. Consequently, in accordance with my invention I provide a pivot between the levers 30 and 31, which is normally fixed with respect to each of the levers, but which is movable with respect to at least one of the levers to provide lost motion therebetween when a predetermined 50 resistance is encountered by the jaws. I provide also a spring carried by one of the levers which resists this lost motion and the pressure of which is adjustable to predetermine the resistance at which the lost motion will come into play, thus limiting the pressure which may be placed by the operator upon the jaws and in turn 55 upon the terminal.

In the present exemplification, the bifurcated ends of the levers 30 and 31 are intercalated as best shown in Figure 3 and the screw bolt 36a passed therethrough securing the levers together and providing the pivot pin 36 therefor. The bifurcations 37, 37a of the lever 31 have the pivot holes 38, 38a therein which closely receive the pivot pin 36 so that the pivot point is substantially fixed with respect to the lever 31, while the bifurcations 39, 39a of the lever 30 have the relatively larger holes 40, 40a through which the pivot pin 36 loosely passes, the holes 38, 38a and 40, 40a being otherwise in register. A spring barrel 41 is disposed transversely of the levers 30 and 31 and has one end bifurcated with its bifurcations 42, 42a intercalated with the bifurcations of the levers and fixed to the bifurcations 39, 39a of the lever 30 as by a small rivet 43. The bifurcations 42, 42a have holes 44, 44a therein regis-

tering with the holes in the bifurcations of the levers and to receive the pivot pin 36 therethrough. The holes 44, 44a are only slightly smaller than the holes 40, 40a in the lever 30 to permit the spring barrel 41 to move with this lever with respect to the pivot pin, and, to enhance the attachment of the spring barrel to the lever 30, the margins 45, 45a of the holes 44, 44a in the bifurcations of the spring barrel are shown laterally extended to form bushings 1 in the holes 40, 40a. The holes 40, 40a are thus slightly reduced in diameter, but are still larger than the holes 38, 38a to permit movement of the pivot pin 36 with respect to the lever 30.

To resist this relative movement between the 15 pivot pin and the lever 30, the spring barrel 41 houses a plunger 46 having a flattened portion 47 which is received between the bifurcations 42, 42a. At its free end, the portion 47 has an arcuately bottomed recess 48 which receives the pivot pin 20 36. The other end of the plunger is pressed upon by the relatively heavy helical compression spring 49 which is also housed in the spring barrel 41 between the plunger and a closure plug 50 for the spring barrel. The plug 50 is threaded 25 30 in the spring barrel and desirably has a diametrical kerf 51 therein, whereby the plug may be advanced or retracted by a screw-driver to adjust the pressure of the spring 49 on the plunger.

In the position of the parts shown in Figure 1, in which the jaws 9 are not exerting pressure, the arcuate bottom 48a of the recess 48 of the plunger, together with the holes 38, 38a in the lever 31, together form a seat for the pivot pin 35 36, which is normally fixed with respect to both the levers 30 and 31 by the spring pressure of the spring 49. At this time the pivot pin is substantially tangent with one side of the holes 44, 44a, as shown in Figure 1. When now the handles 2 40 and 3 are squeezed together by the operator and pressure placed upon a terminal 22 to swage it as described, and as shown in Figures 2 and 3, the pressure of the spring 49 is sufficient, during the first part of this movement of the handles together to prevent movement of the pivot pin 36 with respect to the lever 30, so that all of the pressure exerted by the operator on the handles is transmitted to the jaws 9 and through the jaws to the terminal. When a predetermined amount 50 of pressure has been thus placed on the jaws, as controlled by the adjustable plug 50, the spring 49 yields and any further pressure exerted by the operator on the handles is taken up by the spring 49 and is not transmitted to the jaws 9. 55 In other words, after the jaws 9 have moved together a given distance in response to the squeezing together of the handles 2 and 3, any further squeezing together of these handles causes lost motion which is not transmitted to the jaws 9, 60 but which instead tends to cause movement of the pivot pin 36 from one side of the holes 44, 44a, as shown in Figure 1, to the other side of these holes as shown in Figures 2 and 3. But since the spring 49 resists this lost motion, the 65 pressure of the spring may be so adjusted that the possible lost motion between the pivot pin and the lever is never entirely completed when a terminal is being acted upon and is offering resistance to the inward movement of the jaws 9 70 and therefore no further pressure, beyond the predetermined pressure of the spring 49 above described, can be placed upon the terminal. The spring 49 thus limits the pressure which can be applied on the terminal.

To expedite restoration of the handles 2 and 3 pivot pin therethrough; relatively larger holes in to outermost position when not in operation a conventional elliptic spring 52 may be interposed between the handles.

5 Obviously, the invention is not limited to the details of construction above described for purposes of illustration and furthermore it is not indispensable that all features of the invention be used conjointly as various combinations and 10 sub-combinations may be advantageously employed; the disclosure herein is merely of one embodiment, for purposes of illustration, and my invention is not limited thereto.

Having described my invention, I claim:

15 1. In a hand swaging device, a pair of levers having intercalated bifurcated ends; a pivot pin passing through said ends, one of the levers having holes receiving said pin closely therethrough and the other lever having relatively larger holes 20 loosely receiving said pin, said holes being in register; a spring barrel transverse to the levers, said barrel having one end bifurcated and fixed to the bifurcations of the lever having the larger holes; holes in said bifurcated end of the spring 25 barrel registering with the holes in the lever to which it is fixed; a plunger housed in said barrel, one end of the plunger having an arcuate recess therein receiving the pivot pin and together with the holes in the other lever providing a seat for the pin; and a spring compressed in the barrel and pressing upon the other end of the plunger to maintain 30 the pivot pin normally in fixed position with respect to both levers but yieldable to permit the pin to move with respect to the lever having the larger holes; and a disc closing the end of the cylinder opposite said block and having a central aperture therein concentric with the center about which the said jaws are arranged. 20

5 The structure of claim 4 wherein the spring in the spring barrel is compressed between the plunger and a plug forming a closure for the other end of the barrel and wherein said plug is threadedly received in said barrel to be adjustable to 25 regulate the pressure of the spring on the plunger.

6. In a hand swaging device, a plurality of more than two pointed jaws directed toward a common center and radially movable, a rotatable 30 annulus encircling the jaws and having internal cam surfaces engaging the outer ends of the jaws to move them simultaneously toward said center upon rotation of the annulus in one direction, spring means individual to each jaw for moving 35 the jaw outwardly of said center upon rotation of the annulus in the opposite direction, and means for rotating the annulus, said means comprising a pair of pivoted levers, one of said levers connected in operative relationship with the annulus and one with the jaws to cause relative rotation thereof, said levers pivoted together on a pivot movable with respect to one of the levers to permit lost motion therebetween and an adjustable spring carried by said lever resisting said 40 movement. 45

7. In a hand swaging device, a plurality of more than two jaws directed toward a common center, means for supporting and guiding said jaws, additional means for reciprocating said jaws, and 50 operating means including a pair of levers each pivoted at one end to the respective supporting means and reciprocating means and pivoted intermediate their length to each other, said intermediate pivot being movable with respect to one 55 of the levers and resilient means resisting said movement.

8. In a hand operated device for swaging metallic terminals about metallic electrical conductors including a plurality of more than two jaws directed toward a common center, means for positioning a terminal containing the conductor at said common center, means for supporting and guiding said jaws, additional means for reciprocating said jaws, operating means to apply pressure upon the jaws to swage the terminal upon the conductor including a pair of levers pivoted intermediate their length to each other and pivoted at corresponding ends one upon the jaw supporting means and the other upon the jaw 60 reciprocating means, said intermediate pivot providing a lost motion connection and adjustable means resisting said motion to apply a predetermined pressure upon the terminal. 70

75 9. Swaging mechanism, comprising: a swaging

- element; means for transmitting force to said swaging element, including a lever; and means, for limiting the stress that may be put upon said swaging element, including, lost-motion pivot means pivoting said lever permitting lost motion of said lever, and means opposing such lost motion to prevent such lost motion until the force sought to be transmitted exceeds a predetermined maximum.
10. 10. Swaging mechanism, comprising: a swaging element; means for transmitting force to said swaging element, including a lever; and means, for limiting the stress that may be put upon said swaging element, including, lost-motion pivot means pivoting said lever permitting lost motion of said lever, means opposing such lost motion, to prevent such lost motion until the force sought to be transmitted exceeds a predetermined maximum, and means determining the force at which said opposing means will permit such lost motion, adjustable without changing the position of said lever.
11. 11. Swaging mechanism, comprising: a swaging element; means for transmitting force to said swaging element, including a lever; and means, for limiting the stress that may be put upon said swaging element, including, lost-motion pivot means pivoting said lever permitting lost motion of said lever, and means opposing such lost motion, for preventing such lost motion until the force sought to be transmitted exceeds a predetermined maximum, capable of relieving only as to force in excess of such predetermined maximum, and while relieving as to force in excess of such predetermined maximum, still operating to effect transmission of force up to such predetermined maximum.
12. 12. Swaging mechanism, comprising: a swaging element; means for transmitting force to said swaging element, including a lever; and means, for limiting the stress that may be put upon said swaging element, including, lost-motion pivot means pivoting said lever permitting lost motion of said lever, means opposing such lost motion, for preventing such lost motion until the force sought to be transmitted exceeds a predetermined maximum, capable of relieving only as to force in excess of such predetermined maximum, and while relieving as to force in excess of such predetermined maximum, still operating to effect transmission of force up to such predetermined maximum, and means determining the force at which said opposing means will permit such lost motion, adjustable without changing the position of said lever.
13. 13. A hand swage, comprising: a plurality of swaging elements; means operatively supporting said swaging elements, including a handle portion; means for transmitting force to said swaging elements, including a hand lever having a handle portion; said handle portions being disposed for operation by one hand of an operator, by contraction of the hand, in the nature of plier handles; and means, for limiting the stress that may be put upon said swaging elements, including, lost-motion pivot means fulcruming said lever permitting lost motion of said lever, and means opposing such lost motion, to prevent such lost motion until the force sought to be transmitted exceeds a predetermined maximum.
14. A hand swage, effective to swage a sleeve onto electrical conductor means, comprising: carrier means, leaving a space for reception of the conductor means and a sleeve assembled in relation to be swaged together; a plurality of inwardly directed dies, supported by said carrier means, spaced circumferentially about and relatively movable toward said space; actuating means, mounted for movement relative to said carrier means, and acting upon such movement in one direction to so move said dies to cause said dies to force the sleeve into the conductor means at a plurality of circumferentially spaced places; and operating means, including, a pair of lever handles, and means operatively connecting one of said handles to said carrier means and the other of said handles to said actuating means; said swage comprising means fulcruming said handles to each other, for relative movement substantially in a single plane, operable by one hand of an operator by contraction of the hand, in the nature of plier handles, to effect said relative movement of said actuating means; whereby said swage may be carried and operated entirely by one hand of the operator.
15. A hand swage, effective to swage a sleeve onto electrical conductor means, comprising: carrier means, leaving a space for reception of the conductor means and a sleeve assembled in relation to be swaged together; a plurality of inwardly directed dies, supported by said carrier means, spaced circumferentially about and relatively movable toward said space; actuating means, mounted for movement relative to said carrier means, and acting upon such movement in one direction to so move said dies to cause said dies to force the sleeve into the conductor means at a plurality of circumferentially spaced places; and operating means, including, a pair of lever handles, and means operatively connecting one of said handles to said carrier means and the other of said handles to said actuating means; said swage comprising means fulcruming said handles for relative movement substantially in a single plane, operable by one hand of an operator by contraction of the hand, in the nature of plier handles, to effect said relative movement of said actuating means; whereby said swage may be carried and operated entirely by one hand of the operator.

HARRY A. DOUGLAS.
